UNITED STATES PATENT OFFICE.

WILLIAM ANDREWS, OF NEW YORK, N. Y.

STEAM-RADIATOR.

No. 869,042.

Specification of Letters Patent.

Patented Oct. 22, 1907.

Application filed April 8, 1907; Serial No. 366,905.

To all whom it may concern:

Be it known that I, WILLIAM ANDREWS, a citizen of the United States, residing at New York city, New York, have invented certain new and useful Improvements in Steam-Radiators, of which the following is a clear, full, and exact description.

The object of this invention is to provide a simple, efficient and cheap adjustable steam radiator. In attaining this object I have aimed to utilize such radiators as are already in use, to enable ready and economical change to be made in them as will be apparent hereinafter.

In securing heat variance or adjustment I make use of air which I utilize to subserve my purpose and secure the desired results.

Broadly stated it is my aim to fill with the air laden steam those radiator units, which I do not wish heated to any appreciable degree. The steam condenses and drains off as water, the air accumulates in those radiator units until they become comparatively full of air and relatively cool. To accomplish this—it will be obvious that it is essential to keep open communication at all times between the radiator units so that the air contained in water of condensation may accumulate for some little time after making the necessary adjustments of the valve means for effecting the variation of heat.

Succinctly stated, I provide a normal steam outlet and a steam inlet and an auxiliary pipe to an intermediate portion of the radiator, all in the lower part of the radiator to allow for the drainage of water of condensation, and I provide valve means, preferably in the form of a three-way valve, for closing the normal and auxiliary outlets, or closing either one and opening the other. I also prefer to provide a pet cock or controllable air vent at the top of the radiator units, generally vertically arranged above the auxiliary outlet for the escape of collected air when it is desired to run with all the heating surface in commission. I also prefer to provide a visual indicator to show the position of the three-way adjustment valve.

The scope of my invention will be pointed out in the claims.

In the accompanying drawings, Figure 1 is a side elevation of a Griffing radiator with my invention applied thereto; Fig. 2 is a longitudinal central sectional elevation thereof; Fig. 3 is a side elevation of my invention applied to a type of a modern sectional radiator; Fig. 4 is a longitudinal central sectional elevation thereof; Fig. 5 is a plan of the preferred form of valve and indicator; Fig. 6 is a vertical section of the valve; and Fig. 7 is a transverse section of the valve on line 7—7 Fig. 6.

As illustrated in the drawings, particularly in Figs. 1 and 2, the radiator is composed of a lower header or

box 1 into which are screwed vertical radiator units 2, 3 and 4, all of the usual construction. An inlet valve 5 of the ordinary globe type is provided at one end of the header 1, while a normal outlet pipe 6 leads to a three-way valve 7 at the opposite end. An auxiliary 60 pipe or connection 8 is tapped into the header at any intermediate point depending upon the proportion of the radiator units it may be desirable to cut off. The pipe 8 also leads to the three-way valve 7. At the top of the radiator unit 3 I prefer to locate a pet cock 9. 65

The three-way cock 7, in my preferred form, consists of a casing 10 having a tapered core connecting at its bottom with an outlet pipe 12 and having ports 13 and 14 for the normal outlet pipe 6 and the auxiliary pipe 8, respectively, and having a screw cap 15 centrally 70 bored for the spindle 16 of a tapered valve 17. The spindle 16 is surmounted by a handle 18, and the valve casing 10 is provided with a scale or indicator 19 marked "On," "Aux." or "Off," or similarly marked. The tapered valve or plug 17 is open at the bottom and closed 75 at the top and provided with ports 20 and 21 in its side wall so located that all pipes entering the casing may either be shut off from each other, or the normal outlet 7 connected with outlet 12 and auxiliary pipe 8 cut off, or the normal outlet cut off and the auxiliary pipe 80 8 connected with outlet 12.

The radiator of Figs. 3 and 4 is composed of detachable sections 22 joined by threaded bushings 23. The central section or unit 24 is cast with a boss 25 at its lower end to receive the threaded end of the coupling 85 26 of the pipe 8. The three-way valve, inlet and pet cock are all of the construction shown in Figs. 1 and 2 and operate in the manner described therein.

In operation the three-way valve is turned to "On", the inlet valve opened and steam readily mounts in all 90 the radiator units, being aided, if necessary, by opening the pet cock. When it is desired to moderate the radiated heat the valve is turned to "aux" when the steam will still flow to the bottom of all the radiator units but will leave the radiator at its intermediate 95 point circulating from inlet to the intermediate point. The steam in and under radiator units 4 will condense, leave air in and under the radiator units which not being in the path of circulation do not drain off with the heavier water. Fresh steam with its air takes the place 100 of the water and condensing leaves more air, and so on until the radiator units 4 contain substantially air alone and hence cease to give off any material heat, while the few coils 2 are still active to a maximum extent, for the air in them is kept hot, and mingled with 105 the steam, passes off through circulation.

I claim as my invention:

1. A radiator comprising heating radiator units, a drainage chamber at the base of the units, unobstructed throughout and at all times serving to keep communication 110

open between the units, a steam inlet, and a normal steam outlet to the radiator and an intermediate outlet and means adapted to close the normal outlet and open the intermediate outlet.

5 2. A radiator comprising heating radiator units, a drainage chamber at the base of the units, unobstructed throughout and at all times serving to keep communication open between the units, a steam inlet, and a normal steam outlet to the radiator and an intermediate outlet

and means adapted to close the normal outlet and open 10 the intermediate outlet, said means comprising a single valve, piping from the normal outlet and piping from the intermediate outlet thereto.

Signed at New York city this 6th day of April 1907.

WILLIAM ANDREWS.
